UNITED STATES PATENT OFFICE.

**ALBERT REDFERN, OF PLAINFIELD, NEW JERSEY, ASSIGNOR TO THE STEIN, DOBLIN
LACE CO., A CORPORATION OF NEW YORK.**

DESIGN FOR LACE.

52,146.

Specification for Design.

Patented July 2, 1918.

Application filed January 5, 1918. Serial No. 210,570. Term of patent 3½ years.

To all whom it may concern:

Be it known that I, ALBERT REDFERN, a citizen of the United States, residing at Plainfield, Union county, and State of New Jersey, have invented a certain new and ornamental Design for Lace, of which the following is a specification.

Said design consists in a lace pattern as illustrated in the accompanying drawing wherein is shown a section of a piece of lace embodying the ornamental figures of the pattern and their arrangement in relation to each other, it being understood that these figures are multiplied indefinitely in accord-

ance with the length and width of the piece of lace.

What I claim as new is:

The design for lace as herein shown and described.

In witness whereof, I have hereunto set my hand and seal at New York, New York, this third day of January, A. D. nineteen hundred and eighteen.

ALBERT REDFERN. [L.S.]

Witnesses:

MORTIMER E. ISAACS,
FRED H. STERN.
